METHOD OF PREPARING BODY BLANKS
FOR TEARING STRIP CONTAINERSJohn M. Hothersall, Brooklyn, N. Y., assignor to
American Can Company, New York, N. Y., a
corporation of New Jersey

Application June 3, 1936, Serial No. 83,379

9 Claims. (Cl. 113—15)

The present invention relates to a method of preparing body blanks for key opening tearing strip containers or cans and has particular reference to a method of forming a tongue on the tearing strip from the material of the blank to produce an article such as is disclosed in my pending United States application, Serial Number 28,368, filed June 25, 1935, on "Container".

An object of the invention is the provision of a method of preparing blanks from which the bodies of key opening tearing strip cans are made wherein the tongue for removing the tearing strip is formed in an edge of the blank so that smaller body blanks may be used with a resultant saving in container cost.

Another object is the provision of such a method of preparing body blanks for tearing strip cans wherein the tongue part is formed adjacent an end of the tearing strip which is defined by score lines in the body wall, the tongue being made effective for engagement with an opening key by bending it from its initial position in the blank to an extended position beyond the end of the tearing strip and in longitudinal alignment with the latter.

Numerous other objects and advantages of the invention will be apparent as it is better understood from the following description, which, taken in connection with the accompanying drawings, discloses a preferred embodiment thereof.

Referring to the drawings:

Figure 1 is a perspective view of a tearing strip can having a body made from a blank prepared in accordance with the method of the instant invention, parts of the container being broken away;

Fig. 2 is a sectional fragmentary view on an enlarged scale taken just above the completely formed tearing strip tongue as viewed substantially along the line 2—2 in Fig. 1;

Figs. 3, 4, and 5 are corner fragments of a body blank illustrating the position of the tongue sections relative to the tearing strip in three different stages of its construction;

Fig. 6 is a sectional detail of the tongue construction in an intermediate stage as viewed substantially along the line 6—6 in Fig. 4;

Fig. 7 is a similar view showing the formation of the tongue following the tongue bending operation, this view being a section taken substantially along the line 7—7 in Fig. 5;

Fig. 8 is a fragmentary top plan view of one form of apparatus for carrying out the method steps of the instant invention, the view illustrat-

ing blanks, with sections broken away, in different stages of preparation;

Fig. 9 is an enlarged sectional detail of die members used in cutting the blank to form the tongue, the view being taken substantially along the line 9—9 in Fig. 8;

Fig. 10 is an enlarged top plan view of the tongue bending mechanism illustrated near the center of Fig. 8 as the second stage of preparation, the top of the mechanism being removed;

Figs. 11, 12, and 13 are sectional details illustrating different positions of the movable element of the tongue bending mechanism, Fig. 11 being a view taken substantially along the line 11—11 in Fig. 10, while Figs. 12 and 13 are enlarged views taken substantially along the respective lines 12—12 and 13—13 in Fig. 8;

Fig. 14 is an enlarged sectional detail of one form of tongue folding device, the view being taken substantially along the line 14—14 in Fig. 8;

Fig. 15 is a perspective view of the tongue bending mechanism illustrated in Fig. 10, as observed from a position at right angles to the plan view and illustrating the tongue at the completion of the bending operation;

Figs. 16, 17, and 18 are enlarged sectional details of the tongue folding devices shown in Fig. 8, the views being taken substantially along the line 18—18 in that figure and illustrating the movable parts in different positions during the folding of the tongue against the blank, Fig. 18 showing the tongue bent so that it will not interfere with subsequent handling of the blank.

As a preferred embodiment of the present invention the drawings disclose a method of preparing the body blank for a tearing strip can of the character such as, for example, the one disclosed in my pending United States application hereinbefore mentioned. The can is provided with a tearing strip which encircles the can body being formed with an integral key engaging tongue which extends beyond the edge of the can side seam. Prior to the utilization of the instant invention such a can required an extended body blank long enough to include the longitudinal dimension of the tongue. Hence a great deal of the edge of the blank had to be cut away in blanking out such a projecting tongue with the result that considerable material of the blank was lost or wasted.

In the present invention the tongue is formed at one end of the tearing strip and is within the outer edges of the blank proper or it may be extended along the edge with some or all of

its shorter or width dimension extending out from the blank edge instead of projecting longitudinally beyond. The tongue is formed preferably entirely inside of the adjacent edge of the blank and is partially severed as it remains in position with its longitudinal dimension extending adjacent the blank edge. In other words it is at an angle to the tearing strip instead of longitudinal thereof but it is also integral therewith.

The tearing strip is preferably formed in the body blank wall by score lines which extend from one end of the tongue part longitudinally across the body blank. The tongue part is bent or rotated from its blanked position into a longitudinal relation to the tearing strip so that it projects beyond the edge of the blank. While in this projected position, the tongue is folded or pressed flat into engagement with the tearing strip. After the blank is formed into a can body, the projecting tongue then extends in the conventional position beyond the body side seam.

The can comprises a tubular body 11 (Fig. 1) having a bottom end 12 and a top end or cover 13 which are secured thereto in suitable seams 14. A favorite type of tearing strip can at the present time embodies an inner collar 15 (Figs. 1 and 2). Such a collar may be located adjacent and just beneath the cover 13 and may be united 30 with the body wall in any suitable manner as by cooperating beads 16 formed in body and collar.

Such a collar backs up the tearing strip (indicated by the numeral 18) which preferably encircles the body and extends from one edge of a side seam 19 around the body wall and back to the other edge of the seam. It also provides a seat for the cover when the latter is used as a reclosure for the can after opening and after the tearing strip has been removed.

A tearing strip tongue 21 is formed as an integral part of the body wall and projects beyond a lapped section 22 of the side seam 19. This tongue is adapted to be engaged by a key 20 for removing the tearing strip as when opening the can. A lock section 23 is also formed in the side seam 19 and extends below the end of the lap section 22. Within the bottom seam 14 the side seam has another lapped section 24.

The body 11 of the can is formed from a blank A portions of which are shown in the various 50 figures of the drawings. Only the tongue end of the blank is shown since it is this end which is acted upon. It is to the method of preparing this portion of the blank that the present invention is particularly directed.

The tearing strip 18 is first formed in the blank A in any suitable or usual manner as by 55 partially cutting through or scoring the blank lengthwise and at right angles to the tongue edge in a pair of spaced and parallel score lines 60 29, 31. The score lines do not extend to the tongue edge of the blank but terminate a predetermined distance away to join the tearing strip edge with the tongue 21.

The tongue 21 is next bent from its blank 65 enclosed position and is brought into longitudinal alignment relative to the tearing strip 18. The principal parts of one form of apparatus for doing this is illustrated in the drawings and includes a horizontal table 32 (Figs. 8 to 18, inclusive) 70 along which the flat blanks A are moved horizontally by any suitable means such as a reciprocal feed bar 33 having spaced feed dogs 34. The feed bar is carried in a groove 35 formed in the table. Movement of the feed bar in a forward direction (to the right as viewed in Fig. 8)

successively advances a blank A first to a tongue cutting and notching station B, then to a tongue bending station C and hence to a tongue folding station D from which the blank may be discharged to any suitable place of deposit.

At the cutting station B a marginal portion of the blank A is cut away or notched out as shown in Fig. 3 this being adjacent the short edge now being considered which is contiguous with one end of the tearing strip 18. This cutting action 10 provides a notch 37 having its vertex extending into the terminal end of the score line 29. The score lines 29, 31 are indicated in the drawings and in the description as having been made in the blank prior to the cutting or notching just described but it will be understood that equally satisfactory results may be obtained by scoring or defining the tearing strip after the cutting and notching action.

At the time of notching the tongue 21 is set 20 off or formed in the blank A preferably by a short line of severance 38 (Fig. 3) and a long line of cut 39 joined to the short line in a sharp corner. The opposite end of the long line merges into a rounded corner line 40 which terminates 25 in the score line 31. In this manner the tongue 21 is defined as an integral part of the tearing strip but unlike the usual tongue is located on one side.

A smaller notch 42 is made at the same time 30 in the edge of and within the notch 37 and is located diagonally across from the rounded corner 40 of the severed line 39. This notch 42 sets off a flexing section in the tongue extending between the vertex of the notch and the rounded 35 corner 40 and along which the tongue is later bent. The corners of the blank are cut away to provide the usual notches 43, 44 (Figs. 3 and 8) for the side seam.

This severing of the marginal edge portion of 40 the blank A is effected in any suitable manner as by means of cooperating upper and lower die members 45, 46 (Figs. 8 and 9) which are supported on the table 32. These die members are provided with upper and lower cutting edges 45 47, 48 which cooperate in cutting through the wall of the blank at the proper places, cutting out the notches and severing the tongue along the desired lines while leaving it in place within the plane of the blank. A spring mounted yielding plate 49 disposed in a recess 51 of the lower die member 46 supports the tongue during this severing operation.

After the blank A has thus been notched and the tongue 21 formed, the blank is advanced to 55 the station C (Figs. 8, 10, 11, 12, 13, and 15). Here the tongue is bent along its flexing section defined by the notch 42, the tongue being thereupon displaced out of the plane of the blank. In this displacement it is rotated by being bent around a mandrel as will be later described in detail and is brought into a position substantially parallel to the blank where its longitudinal axis is substantially at right angles to its former position. This places the tongue so that its longitudinal center line is in the same plane as the longitudinal center of the tearing strip, that is the tongue extends beyond the edge of the blank as shown in Fig. 4. A rounded loop part 53 (Fig. 6) is formed in the tongue by this bending movement.

This positioning of the tongue 21 is effected by a suitable bending device 55 which includes a block 56 (Fig. 15) set into a recess 57 formed in the top of the table 32 at an angle of substan-

tially 45 degrees with the edge of a positioned blank. The top of the block extends above the top of the table and at its forward end it is cut away as at 58 flush with the table top to permit advancing blanks to pass over it. Its sides are cut back in wedge fashion as at 59 to provide clearance for the passing of the blank on one side and for the bending of the tongue on the other.

10 The block is formed with a longitudinal horizontal bore 62 having its central axis flush and parallel with the top of the table. A cylindrical bending element 63 is located in the bore and is rocked or partially rotated periodically in any 15 suitable manner. The forward end of the bending element is cut away on an angle as at 65 (Fig. 10) providing a flat shelf part 66 which, when the element is in one position, is flush with the top of the table. This also permits passage 20 of the blank over it.

A finger projection 67 (Fig. 13) of the shelf 66 extends under the tongue 21 adjacent its flexing section and this projection extends into a recess 68 formed in the end of the block 56.

25 Rotation of the bending element 63 lifts the projection 67 as the bending element moves on its axis and the projection engaging the tongue 21 moves it out of the plane of the blank.

This movement of the projection forces the 30 tongue against a tapered face 71 of an anvil 72 (Fig. 12) which is disposed over the top of the blank adjacent the flat top 58 of the block 56. The anvil is set at an angle of substantially 45 degrees, with the lower edge of its tapered face 35 in alignment with the flexing section of the tongue as shown in Fig. 10 so that the tongue will be bent along this line.

During this bending of the tongue 21, the top surface of the latter is wiped against the bottom 40 of an overhanging plate 74 as shown in Fig. 12. The plate is vertically spaced above the top of the positioned blank and is secured to the top of the block 56. It is to the bottom of the overhanging end of this plate that the anvil 72 is secured. 45 At the forward end of the plate its bottom surface curves downwardly as at 76 (Fig. 13) and extends parallel with an inclined face 77 of the finger projection 67 when the latter is in the position shown in Figs. 12 and 13. It is this curved surface 76 and the bending action of the finger projection 67 that forms the loop 53 in the tongue.

The plate prevents the tongue from being lifted straight up while it is being bent, and during the 50 wiping action keeps the tongue substantially horizontal. This wiping action in effect rotates the tongue horizontally through an angle of substantially 90 degrees, the while slightly lifting it from its original position shown in Fig. 10 into a position in longitudinal alignment with the 55 tearing strip 18 as shown in Fig. 15.

The finger projection 67 returns to its position within the recess 68 and the blank A is moved to the next or tongue folding station D (Figs. 8, 14, 16, 17, and 18). At this station the loop 60 part 53 (Fig. 6) of the bent tongue 21 is pressed down and folded, bringing the tongue into tight fitting engagement against the tearing strip 18 as shown in Figs. 5 and 7. At the same time the part of the tongue which extends beyond the edge 65 of the blank is preferably bent down as shown in dot and dash lines in Fig. 7 so that it will be out of the way during handling of the blank for subsequent operations thereon.

The folding of the tongue loop 53 is effected 70 by any suitable mechanism, for example, a mech-

anism comprising upper and lower die members 81, 82 illustrated in part in Figs. 16, 17, and 18 of the drawings. The lower die member 82 is stationary and is seated in a recess 83 formed in the table 32 with its top surface flush with the 75 top of the table. One end of the lower die member extends under the tearing strip 18 of the blank and supports the latter during the folding action.

The upper die member 81 is vertically movable 10 and is provided with a stepped section 85 having a hammer nose 86 which when the member is lowered is brought into contact with the tongue loop 53. This presses or folds it flat against the tearing strip 18 as shown in Fig. 17. A projecting guide block 87 formed integrally with the hammer nose engages the side of the tongue and holds it against shifting, from its aligned position with the tearing strip, while the loop is being folded. A clearance recess 88 formed in 20 the table 32 adjacent the stationary die member 82, permits the guide block to descend below the top of the table while the tongue is being folded.

An auxiliary die member 89 is preferably disposed adjacent the upper die member 81 and this member is vertically movable into engagement with the folded tongue 21. The full movement of this auxiliary die results in bending the tongue out of the way for subsequent handling 30 of the blank as hereinbefore mentioned. The bent tongue is indicated by the numeral 92 (Figs. 7 and 18). This bending of the tongue is effected by a foot 93 formed on the bottom of the member 89 and the tongue after bending extends down into the clearance recess 88 while the hammer nose 86 of the die member 81 holds the folded section of the tongue against displacement.

The lower die member 82 serves as an anvil 40 for this operation. An edge of the die member extends into the recess 88 and terminates adjacent the edge of the blank. The blank is discharged from station D and may be conveyed 45 from the table 32 to any suitable place of deposit. A groove 95 in the table and communicating with the recess 88 provides clearance space for the turned down tongue as the blank is moved along this part of the table.

By constructing a tongue in this manner a great 50 deal of material is saved in the blank which need only be large enough to form the desired size of body. Where the tongue is entirely inside of the blank edge the lock seam section 23 of the body determines the over-all dimension of 55 the blank. Since the tongue is extended beyond the edge of the body at the lap section 22, the tongue width in the preferred form as described comes out of a blank part about equal to that forming the hook of the lock seam section 23 60 and consequently a much smaller blank produces the same size of can.

It is thought that the invention and many of its attendant advantages will be understood from the foregoing description, and it will be apparent that various changes may be made in the steps of the process described and their order of accomplishment without departing from the spirit and scope of the invention or sacrificing all of its material advantages, the process hereinbefore described being merely a preferred embodiment thereof.

I claim:

1. The method of preparing a container body blank having a removable tearing strip, which 75

comprises forming a tongue in said blank which is integral with a tearing strip formed in the blank, said tongue being disposed at an angle to the tearing strip, and bending the tongue into longitudinal alignment with the tearing strip.

2. The method of preparing a container body blank having a removable tearing strip, which comprises cutting a line of severance in said blank to define a tongue integral with a tearing strip formed in the blank, said tongue being disposed at an angle to the tearing strip, and bending the tongue into longitudinal alignment with the tearing strip.

15 3. The method of preparing a container body blank having a removable tearing strip, which comprises cutting a line of severance in said blank to define a tongue which is integral with a tearing strip formed in the blank, said tongue being disposed at an angle to the tearing strip and confined within the marginal edges of the blank, and bending the tongue into longitudinal alignment with the tearing strip.

25 4. The method of preparing a container body blank having a tearing strip, which comprises forming a tongue in said blank which is integral with a tearing strip formed in the blank, said tongue being disposed at an angle to the tearing strip, bending the tongue out of the plane of the blank by moving its free end about an axis and into a position with its longitudinal center line substantially parallel with the longitudinal center line of the tearing strip, and pressing the tongue into engagement with the tearing strip 30 while forming a folded portion of the tongue at the junction of tongue and tearing strip.

35 5. The method of preparing a container body blank having a tearing strip, which comprises forming a tongue in said blank which is integral with a tearing strip formed in the blank, said tongue being disposed at an angle to the tearing strip, bending the tongue out of the plane of the blank by moving its free end about an axis while forming a loop in the tongue and bringing it into 40 a position with its longitudinal center line substantially parallel with the longitudinal center line of the tearing strip, pressing the tongue into engagement with the tearing strip, and holding said tongue in a line of movement during the 45 pressing action to form a folded portion of the tongue at the junction of tongue and tearing strip.

6. The method of preparing a container body blank having a tearing strip, which comprises forming a tongue in said blank which is integral with a tearing strip contained within the blank, said tongue being disposed at an angle to the tearing strip, bending the tongue into longitudinal alignment with the tearing strip so that a portion of the tongue overlaps and engages the same and the remainder of the tongue projects beyond the edge of the blank, holding said engaging portion of said tongue, and bending the said remainder at an angle to facilitate further handling of the blank during subsequent operations thereon. 5 10

7. The method of preparing a container body blank having a removable tearing strip, which 15 comprises forming a tongue in said blank which is integral with a tearing strip formed in the blank, said tongue being disposed at an angle to the tearing strip, notching said tongue to provide a flexing section therein, and bending the tongue along 20 said flexing section as an axis and into longitudinal alignment with the tearing strip.

8. The method of preparing a container body blank having a tearing strip, which comprises forming a tongue in said blank which is integral 25 with a tearing strip formed in the blank, said tongue being disposed at an angle to the tearing strip, notching said tongue to provide a flexing section therein, displacing said tongue out of the plane of the blank by bending it along an 30 axis and simultaneously rotating it to a plane substantially parallel with the plane of the blank and into centralized longitudinal alignment with the tearing strip so that a portion of the tongue overlaps the tearing strip, and folding said tongue 35 at said flexing section and into engagement with said tearing strip the while maintaining the alignment and centralized position of the tongue relative to the tearing strip.

9. The method of preparing a container body blank having a removable tearing strip, which 40 comprises notching a marginal edge of said blank as an incident to the preparation of a side seam, forming a tongue along said notched marginal edge which is integral with a tearing strip formed 45 in the blank, said tongue being disposed at an angle to the tearing strip, and bending the tongue into longitudinal alignment with the tearing strip.

JOHN M. HOTHERSALL.
